INVENTOR.
R. E. Van Patten
BY
Watson E. Coleman
ATTORNEY.

UNITED STATES PATENT OFFICE.

ROBERT E. VAN PATTEN, OF HILSDALE, MICHIGAN.

CURTAIN-HANGING MEANS.

Application filed October 15, 1923. Serial No. 668,637.

To all whom it may concern:

Be it known that I, ROBERT E. VAN PATTEN, a citizen of the United States, residing at Hillsdale, in the county of Hillsdale and

5 State of Michigan, have invented certain new and useful Improvements in Curtain-Hanging Means, of which the following is a specification, reference being had to the accompanying drawings.

10 This invention relates to curtain hanging means and it is an object of the invention to provide novel and improved means of this character whereby a curtain may be readily and conveniently supported or hung 15 in desired position and in a manner whereby the curtain may be conveniently moved into open or closed position.

Another object of the invention is to provide means of this general character embodying a novel and improved ring having associated therewith means for effectively clamping the curtain thereto yet permitting the ready removal or application of the curtain as desired.

25 The invention consists in the details of construction and in the combination and arrangement of the several parts of my improved curtain hanging means whereby certain important advantages are attained and 30 the device rendered simpler, less expensive and otherwise more convenient and advantageous for use, as will be hereinafter more fully set forth.

The novel features of my invention will 35 hereinafter be definitely claimed.

In order that my invention may be the better understood, I will now proceed to describe the same with reference to the accompanying drawings, wherein:—

40 Figure 1 is a view in perspective illustrating curtains hung or supported in accordance with an embodiment of my invention; Figure 2 is an enlarged transverse sectional view illustrating in detail a ring and the clamping means associated therewith;

45 Figure 3 is a sectional view taken substantially on the line 3—3 of Figure 2;

50 Figure 4 is a view in perspective of a ring unapplied;

55 Figure 5 is an elevational view of the clamping member for coaction with the ring as illustrated in Figure 4;

Figure 6 is a fragmentary view in perspective illustrating a guide member as herein embodied.

As disclosed in the accompanying drawings, 1 denotes a curtain rod adapted to be supported in working position in any desired manner and which preferably has its longitudinal marginal portions returned to provide the flanges 2. The rod 1 is preferably of the type disclosed in my pending application Serial No. 650,890 filed July 11, 1923.

Slidably mounted upon the rod 1 is a plurality of rings 3, each of said rings being substantially elliptical in form and having the bar thereof of channel formation in cross section with the open face thereof outwardly disposed whereby the periphery of the ring has disposed entirely therearound a groove or channel 4.

Associated with each of the rings 3 is a clamping member 5 substantially U-shaped in form and possessing a certain degree of inherent resiliency whereby the same may be readily engaged over a ring 3 and in a manner to effectively hold or clamp a portion of a curtain C to said ring. The intermediate portion of the member 5 is defined by an outstanding loop or extension 6 to provide means to facilitate the application or removal of the member 5 while the free extremities of the side arms of said member 7 are provided with the converging extensions 8. The extensions 7 facilitate the clamping action of the member 5 while the extensions 8 serve to facilitate the application of the member 5 in working position upon the ring 3.

Threaded through the rings 3 are the flexible members or cords 9, said cords being also disposed through a guide member or hook 10 positioned adjacent each end of the rod 1. As herein disclosed each guide member or hook 10 is formed of a single strand of material with its shank inwardly and downwardly offset, as at 11, (Figure 6) to engage between the body of the rod 1 and the lower flange 2, said shank being of such length as to have its outer end engageable between the body one and the upper flange 2.

One of the flexible members or cords 9 is suitably secured, as at 12, to the ring 3 adjacent the inner end of one of the curtains while the second member or cord 9 is suitably connected to the inner ring of a second curtain and when the curtains are in closed position as illustrated in Figure 1, a depending end of each of the members or cords

9 is of a length greater than the opposite depending end.

When it is desired to move one or both of the curtains into open position pull is imposed upon the shorter depending portion 5 of the cord or member 9 which is also true in the event the curtains are open and it is desired to move one or both of said curtains into closed position.

10 From the foregoing description it is thought to be obvious that a curtain hanging means constructed in accordance with my invention is particularly well adapted for use by reason of the convenience and facility with which it may be assembled and 15 operated, and it will also be obvious that my invention is susceptible of some change and modification without departing from the principles and spirit thereof and for this

reason I do not wish to be understood as 20 limiting myself to the precise arrangement and formation of the several parts herein shown in carrying out my invention in practice except as hereinafter claimed.

25 I claim:—

As a new article of manufacture, a curtain ring, the periphery of said ring being provided therearound with a groove, and a substantially U-shaped clamping member adapted to engage within the groove of the 30 ring, the extremities of the clamping member being provided with inwardly disposed extensions continued by outwardly directed extensions.

35 In testimony whereof I hereunto affix my signature.

ROBERT E. VAN PATTEN.
